UNITED STATES PATENT OFFICE.

PHILIP NEDDO, OF BARRE, VERMONT.

CAR-COUPING.

No. 889,033.

Specification of Letters Patent.

Patented May 26, 1908.

Application filed September 19, 1906. Serial No. 335,317.

To all whom it may concern:

Be it known that I, PHILIP NEDDO, a citizen of the United States, residing at Barre, in the county of Washington and State of 5 Vermont, have invented new and useful Improvements in Car-Couplers, of which the following is a specification.

This invention relates to car couplers of the type embodying a draw head carrying a 10 pivoted coupling knuckle adapted for movement to and from engaging or coupling position, and has for its objects to produce a comparatively simple, inexpensive device of this character in which the knuckle will be 15 firmly and securely locked in coupling position, one wherein the knuckle may be conveniently released when circumstances require, and one in which the knuckle will, when released, spring automatically to uncoupling position.

With these and other objects in view, the invention comprises the novel features of construction and combination of parts more fully hereinafter described.

In the accompanying drawings: Figure 1 is a horizontal section taken longitudinally through a draw head, showing the same equipped with a coupling mechanism embodying the invention. Fig. 2 is a vertical, 25 longitudinal section taken on the line 2—2 of Fig. 1. Fig. 3 is a detail perspective view of the locking member and pin.

Referring to the drawings, 1 designates a draw bar having a head 2 hollowed to present an internal chamber 3 and provided at 35 one side with a forwardly projecting guide finger 4 and at its other side with a pair of vertically spaced forwardly extending bearing ears 5, there being arranged in the chamber 3 a locking member 6 in the form of an L-shaped bell crank lever pivoted at its elbow on a vertical pintle 7 and presenting a transversely extending contact portion or finger 8 and a forwardly extending engaging portion or finger disposed parallel with the longitudinal axis of the bar and provided in its outer edge at a point adjacent its forward end with a vertical opening or recess 9 adapted to receive a vertically movable 40 coupling member or pin 10 in turn entered through suitable openings in the head and designed for movement to release the locking member 6. Pivoted between the ears 5 on a vertical pintle 11 is a coupling knuckle 55 12 having a rearwardly extending portion or arm 13 adapted to enter the chamber 3

and for engagement by the locking member 6 to hold the knuckle in coupling position.

The pin 10, which is suspended at the forward end of an operating lever 14, is connected with the locking member 6 by means of a flexible connection or chain 15 engaged at one end with the outer edge of the forward portion of the locking member, the chain being passed between its ends loosely through a guide opening 16 formed in the side wall of the draw head 2.

In practice, when the knuckle 12 is in active coupling position, as seen in Fig. 1, the forwardly extending portion of the locking member will bear against the end of arm 13 for holding the knuckle against movement, the locking member being in turn fixed by means of the coupling pin 10. When, however, the pin is raised through the medium of the lever 14 for releasing the locking member 6 the knuckle 12 will be free to swing to uncoupling position, it being mentioned in this connection that the upward movement of the pin, to prevent its entire withdrawal from the draw-head, will be limited by the chain 15, which performs the additional function of moving the locking member 6 to non-engaging position and further that the member 6 in its movement by the chain initiates the uncoupling movement of the knuckle. When the knuckle 12 is thrown inward to coupling position, the inner end of arm 13 will contact with the portion or finger 8 of the locking member, thereby swinging the latter automatically to locking position to be secured by the pin 10 in the manner explained. It will be observed that in the operation of the device the knuckle will swing freely to coupling or uncoupling position and will, in its movements, automatically seat the locking member 6, and further that the knuckle will be firmly and securely locked in coupling position through the medium of the locking member and coupling pin, which latter automatically seats in engagement with the locking member when in locking position.

Having thus described my invention, what I claim is:

1. In a car coupler, a draw head having a chamber, a coupling knuckle pivoted in the head and having an arm adapted to swing into and out of the chamber, a locking member permanently pivoted in the chamber to engage the arm to hold the knuckle in coupling position, a coupling pin extending

through the head to engage the locking member, an operating lever flexibly connected with the coupling pin, and flexible elements connected with the lever and with the locking member and the pin and of such length as to prevent the pin from being withdrawn from the head.

2. In a car coupler, a draw head having a chamber provided with a lateral opening, a 10 coupling knuckle permanently pivoted on the head and provided with an arm movable in and out of the chamber, a locking member pivoted in the head to be actuated by the

arm and to hold the arm in locked position, a pin extending through the head and engaging the locking member, a chain connected with the locking member and extending through the opening of the draw head, and an operating lever connected with the coupling pin and chain. 15

In testimony whereof, I affix my signature in presence of two witnesses.

PHILIP NEDDO.
